Primary Examiner — Patricia Palasik

(74) Attorney, Agent, or Firm — Workman Nydegger

(57) **CLAIM**

The ornamental design for a stereolithography machine, as shown and described.

DESCRIPTION

FIG. 1 is a perspective view of a stereolithography machine showing my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken lines shown represent unclaimed environmental subject matter and form no part of the claimed design.
